UNITED STATES PATENT OFFICE

101,394

DESIGN FOR A COMBINED SINK AND CABINET

Francis John Osuch, Detroit, Mich., assignor to
Robot-Hand Corporation, Detroit, Mich., a
corporation of Delaware

Application December 12, 1935, Serial No. 60,022

Term of patent 3½ years

To all whom it may concern:

Be it known that I, Francis John Osuch, a citizen of the United States, residing at Detroit, in the county of Wayne and State of Michigan, have invented a new, original, and ornamental Design for a Combined Sink and Cabinet, of which the following is a specification, reference being had to the accompanying drawing, forming part thereof.

The figure is a perspective view of a combined sink and cabinet showing my new design; the rear and end not shown present substantially plane surfaces.

As shown in the drawing, the essential feature

of my design comprises a substantially rectangular top provided with a sink basin of continuous arcuate formation, a front wall divided into a central portion which is louvered at the top only and is provided with handles at the lower part only, and the front is also divided into two identical portions, one on each side of said central portion, said side portions having a horizontally disposed drawer front at the upper part and vertically extending door portions below.

I claim:

The ornamental design for a combined sink and cabinet, as shown and described.

FRANCIS JOHN OSUCH.
